CIRCULAR KNITTING MACHINE

Arthur A. Caudle, Hendersonville, N. C., assignor
to James P. Grey, Charles L. Grey, and James
P. Grey, Jr., a co-partnership doing business as
Grey Hosiery Mills, Hendersonville, N. C.

Application December 8, 1934, Serial No. 756,692

3 Claims. (Cl. 66—8)

This invention relates to circular knitting machines for knitting silk stockings and is adapted to be applied to a machine of the Scott and Williams type in which a single silk thread is employed in knitting the leg and foot portions of a stocking, and a separate yarn is employed in knitting the toe and heel portions thereof.

It is a well known fact that natural silk threads are formed with intermittent and relatively heavy and light portions throughout their lengths. Sometimes these relatively heavy portions extend for twenty or more feet, and consequently when a thread is knitted into tubular form these heavy portions of the thread are laid in adjacent convolutions or courses which give to the stocking the appearance of having a stripe or ring extending therearound. Sometimes this stripe is of a relatively narrow width, and sometimes it is relatively very wide, the width of the stripe depending upon the length of the heavy portion of the thread. After the stockings have been knitted, they are dyed and the relatively heavy portions of the silk have the appearance of being much darker in shade than the relatively light sections.

The principal object of this invention is to provide a circular knitting machine with means for employing a plurality of silk threads when knitting the leg and foot portions of the stocking, whereby the heavy or thick portions of the thread will be dispersed to such an extent that the stripes or rings will be eliminated.

Figure 1 is an elevation of a circular knitting machine with certain parts being omitted, but showing my invention applied thereto;

Figure 2 is a plan view of the head, certain of the parts being omitted;

Figure 3 is an enlarged detail elevation of the stitch cams;

Figure 4 is a bottom plan view of the sinker ring;

Figure 5 is a vertical cross section taken through said ring;

Figure 6 is a plan view partly in section showing the dial cap, the sinker ring, the needles and sinkers, and the thread cutters and clamps;

Figure 7 is an elevation partly in section of the dial frame and showing particularly the thread cutters and clamps;

Figure 8 is an enlarged section showing the mounting of one of the auxiliary stitch cams; and

Figure 9 is a detail perspective view of the pattern cam.

55 My invention is adapted to be applied, with

slight modifications, to the well known Scott and Williams circular knitting machine employed for knitting tubular silk stockings, and therefore I have shown in the accompanying drawings only those parts of such a machine as will enable any one skilled in the art to understand the nature and operation of my invention.

This Scott and Williams machine includes a main head 5 in which the cylinder 6 is rotatably mounted. This cylinder carries the latched needles 7 which are vertically reciprocated in the usual manner by means of a "stitch cam" A fixed to a cam ring 8 mounted on the head and receiving the needle butts 9. A thread guide finger 10 which is mounted on the head functions to guide a silk thread a to the needles at the stitch cam A. Cooperating with the needles to form the stitches are the usual sinkers 11 which are actuated by means of a stationary sinker ring 12 mounted on the head and provided with the usual horizontally extending cam groove 12a for receiving the sinker butts. Fixed to the cylinder is a driven gear 13 which is actuated by the usual drive mechanism for rotating the cylinder in an anti-clockwise direction when knitting the leg and foot portions of a stocking and for oscillating the cylinder when knitting the heel and toe portions of the stocking. Pivoted to the head 5 above the cylinder 6 is the usual frame 14 carrying the dial 15 which is rotated in the usual manner, and fixed to the frame 14 above the dial is the usual cap 16. Upon the completion of the leg portion, as well as the foot portion, the thread a is clamped and cut by means of a pivoted clamp 17 and a pivoted cutter blade 18 which are both mounted on the cap 16. To this end, a rotary pattern drum 19 is mounted on the main frame and is rotated once for each completed stocking by the usual driving connections. Spaced circumferential cams 20, 21 are fixed to the drum for lifting a vertically disposed thrust rod 22, the upper end thereof being disposed under and engageable with the horizontal arm 23 of a bell crank lever 24 pivoted at 25 to the dial frame 14. The vertical arm 26 of said lever terminates in an inwardly extending arm 27 to which is connected the upper end of a vertical link 28, the lower end of the link being pivotally connected to one end of the pivoted thread cutter blade 18. A spring pusher 29 is mounted on the frame 14 directly under the arm 27 and functions to normally maintain the throat of the cutter blade 18 in open position for freely receiving the thread. A stationary ledger blade 30 is mounted on the cap 16 for cooperation with the movable blade 18. 55

The thread clamp 17 which is pivoted on the cap 16 is normally pressed downwardly by a spring 31, and is raised by upward movement of the cutter blade 18 to allow the thread to pass thereunder. As soon as the cams 20, 21 pass under the thrust bar, the cutter throat will be opened and the clamp elevated, and as soon as the cams leave the thrust bar the cutter blade and the clamp will be actuated by means of the spring 10 pusher 29. As soon as the leg and foot portions have been respectively completed, a thread change-over is made in the usual manner, the cylinder is oscillated, and the heel and toe are thereby knitted. These extra threads or yarns 15 which are employed in knitting the heel and toe portions of a stocking are directed to the needles through vertically movable thread guiding fingers which are operated in proper timed relation from the pattern drum 19; these fingers and operating connections, however, are not shown, as they are well known in the art.

From the foregoing it will be observed that the thread guide finger 10, the stitch cam A, the needles 7, the sinkers 11, and the sinker ring 12 constitute a main or primary set of knitting instrumentalities.

In applying my invention to the above described machine, I provide two auxiliary and vertically movable thread guide fingers 32, 33 which 30 are mounted for reciprocation in guide brackets 34, 35 attached to the dial frame 14 at spaced points in advance of the stitch cam A. Fixed to the brackets and extending outwardly therefrom are guides 36, 37 for leading the auxiliary 35 silk threads b and c to the lower ends of the thread fingers 32, 33. Fixed to the upper end of the thread finger 32 is a laterally extending arm 38 which extends under and has sliding connection with a pin 39 fixed to the upper end of the 40 finger 33, whereby when the finger 32 is elevated the finger 33 will be elevated therewith. Fixed to and extending outwardly from the upper end of the thread finger 32 is a pin 40 and extending under this pin and having sliding contact therewith is the free end of a lever arm 41 which is pivoted at 42 on the dial frame 14. The downward movement of this lever arm is limited by a stop 43 which is also fixed to said dial frame. Coil springs 44, 45 have their upper ends respectively connected to the fingers 32, 33 and their lower ends connected to the brackets 34, 35 and function to normally hold the thread fingers in cooperative relation with the needles. These thread fingers 32, 33 are automatically withdrawn 50 from their cooperative relation with the needles at the beginning of the heel portion and the toe portion, and are automatically returned to cooperative relation with the needles upon the completion of said heel and toe portion whereby the 55 three threads, a, b, and c, will be utilized in knitting three courses during the formation of the leg and foot portions of the stocking. In order to swing the lever arm 41 upwardly and thereby elevate the thread fingers 32, 33, I have employed a vertically disposed thrust rod 46 which is movable in upper and lower guides 47, 48, as shown in Figure 1. The upper end of this thrust rod 46 is positioned under an adjustable eccentric 49 attached to the lever arm 41. The lower end of the lever cooperates with spaced circumferential 60 cams 50, 51 which are fixed to the pattern drum 19.

Cooperating with the needle butts 9 and located in cooperative relation with the thread fingers 32, 33 are spaced stitch cams B and C. These

two cams are movable horizontally into and out of engagement with the needle butts, and when these cams are in operative position they cooperate with stationary cam plates 52, 53 fixed to the cam ring 8, to thereby form between the stitch 5 cam B and the plate 52 and between the stitch cam C and the plate 53 downwardly inclined grooves for receiving the needle butts, as shown in Figure 3. The stitch cams B and C are supported on the head 5 for horizontal reciprocations 10 and their movements are controlled by the pattern drum 19. The cams B and C are rigidly attached to the inner ends of bars 54, 55 which are slidably mounted in bearing blocks 56, 57 fixed to the head 5, said slide bars being movable in 15 different radial planes with respect to the cylinder 6. Mounted in each bearing block is a spring plunger 58 which bears against a depending shoulder 59 carried by the inner end of the bar and functions to yieldably retain the stitch cam 20 carried thereby in normal cooperative relation with the needles. Mounted in the outer end of each slide bar is an adjustable stop screw 60 which is adapted to cooperate with the associated bearing block and thereby limit the inward movement of the slide bar.

In order to periodically retract the stitch cams B and C upon completion of the leg and foot portions of the stocking, I have provided the following mechanism:

Vertically disposed levers 61, 62 are fulcrumed intermediate their ends to the periphery of the head 5, and links 63, 64 are pivotally connected to the upper ends of these levers and to the slide bars 54, 55. The lower ends of the levers 61, 62 35 are pivotally connected by links 65, 66 to rock arms 67, 68 fixed to and depending from a rock shaft 69 journaled in brackets 70, 70 depending from head 5. An inwardly extending rock arm 71 is fixed to one end of the rock shaft 69 and 40 a vertically disposed thrust rod 72 has its upper end pivotally connected to the rock arm 71. This thrust rod extends downwardly through the lower guide 48 and the lower end thereof cooperates with spaced circumferential cams 73, 74 fixed to 45 the pattern drum 19.

When the needles are drawn down by the stitch cams B and C, it is necessary to shift the associated sinkers 11 in order to form stitches, as will be readily understood. I have, therefore, 50 provided two spaced sinker cams 75, 76, as shown particularly in Figures 4 and 5, and these two cams are disposed in cooperative relation to said stitch cams B and C. The sinker ring 12 has its inner face cut away as at 77, 78 to 55 receive the sinker cams 75, 76, and these two cams are rigidly mounted on an arm 79 which is pivoted at one end as at 80 to a post 81 fixed to the sinker ring 12, the arm 79 being located above the ring. Normally the arm 79 is in a 60 horizontal position, as shown in Figure 1, wherein the sinker cams 75, 76 are normally disposed in cooperative relation with the needles. When, however, the thread fingers 32, 33 are elevated upon the completion of the leg portion and foot 65 portion, the sinker cams are likewise elevated so as to throw out these two extra threads b and c to permit the cylinder 6 to be oscillated and thereby form the heel and toe portions of the stocking. To this end the arm 79 is normally 70 held in its horizontal position against upward movement by means of an extension arm 82 fixed to the upper end of the thrust rod 46. A coil spring 83 surrounds the pivot 80 of this arm and one end engages the latter to normally 75

urge the arm upwardly. Consequently, when the thrust rod 46 is elevated by the associated cams 50, 51 on the pattern drum 19, the thread fingers 32, 33 will be elevated and simultaneously therewith the extension arm 82 will be elevated whereupon the cam carrying arm 19 will be swung upwardly by means of said spring 83. A post 84 is threadably engaged in the sinker ring 12 in close proximity to the arm 19, and a vertically adjustable stop 85 is mounted on the upper end of said post above said arm to limit the upward movement of the latter.

When the leg and foot portions of the stocking have been knitted, it is desirable to cut not only the thread *a* as previously explained, but also to cut the threads *b* and *c*. It is also desirable to clamp the supply ends of these two threads *b* and *c* after they have been cut. To this end, I have mounted a bracket 86 on the dial cap 16 and have fulcrumed a movable cutting blade 87 on said bracket by means of a pivot screw 88. A stationary ledger blade 89 is fixed to the bracket 86 for cooperative engagement with the movable blade 87. A vertically disposed link 90 has its lower end pivotally connected to the end of the movable blade 87 opposite the throat thereof, and its upper end connected to an arm of the lever 24. A thread clamp 91 formed of flat spring metal is attached 30 to the dial cap, as shown in Figure 6. The two threads *b* and *c* are led under the clamp 91 and across the throat of the thread cutter 87, 89, and when the throat is opened these two threads will be received therein, and consequently, when 35 the throat is closed said threads will be cut and the supply ends of the threads will be clamped by the clamp 91. Thus the lever 24 functions to operate simultaneously the thread cutter 88, 30 for the thread *a* and also the thread cutter 87, 89 for the threads *b* and *c*.

In the operation of my invention, we will assume that the leg portion of the stocking is being knitted. At this time the cylinder is being rotated, the thread fingers 32 and 33 are disposed in cooperative relation to the needles, and the stitch cams B and C, as well as the sinker cams 75, 76, are likewise disposed in cooperative relation to the needles.

The needle draws thread *a* down by stationary 50 stitch cam A to form a loop and a sinker passes into this loop to thereby form the first stitch. The needle is then raised to shed the stitch by a cam 92 which is mounted on the slide bar 54 of the auxiliary stitch cam B, as shown in 55 Figures 2 and 3. The needle is then lowered to engage thread *b* and form a stitch by means of a cooperating sinker, the latter being moved by the cam 75, and this stitch is then shed by a cam 93 which is mounted on the slide bar 55 of the auxiliary stitch cam C. The needle is then lowered to engage thread *c* and form a stitch by means of a cooperating sinker, the latter being moved by the cam 76. This third stitch however is not shed until said stitch reaches a cam 60 65 94 which is located on the cam ring 8 just in advance of cam A. Thus, it will be seen that by means of my invention, three silk threads, *a*, *b*, and *c*, are fed into the machine, and after the initial start, the courses are formed simultaneously, and that said courses are arranged above one another. Consequently, two courses formed by threads *b* and *c* will be positioned intermediate adjacent courses formed by the thread *a*. Practice has demonstrated that if only 70 75 one extra thread were employed the dark spots

or rings are not entirely eliminated, but by the use of two extra threads said dark spots or rings are entirely eliminated.

When the leg portion has been completed, the thread fingers 32, 33 are raised out of their cooperative relation with the needles, and the stitch cams B and C, and shedding cams 92, 93, as well as the sinker cams 75, 76, are likewise moved out of cooperative relation with the needles, and both the thread cutters are actuated to cut the three threads, *a*, *b*, and *c*. The supply ends of the threads are then clamped as previously described. The cylinder is then oscillated to effect the knitting of the heel portion of the stocking by a yarn, in the well-known manner. Upon 15 completion of the heel portion, the thread fingers 32, 33 are lowered into cooperative position with the needles, and the stitch cams B and C, as well as the sinker cams 75, 76, are likewise moved into cooperative position with the needles to form 20 the foot portion. Upon completion of the foot portion the above mentioned instrumentalities are withdrawn from their cooperative relation with the needles and the cylinder is again oscillated to effect the knitting of the toe portion of 25 the stocking in the well known manner.

It will be understood that various changes may be made in the specific construction and relative arrangement of the parts without departing from the invention as defined in the claims. 30

I claim:

1. In a circular knitting machine for knitting stockings, the combination of a frame, a stationary head, an alternately rotary and oscillatory needle-carrying cylinder mounted in said head, 35 a dial frame supported on the head above the cylinder, a rotary drum mounted on the frame below the head, and a main set of cooperating knitting instrumentalities for successively knitting the leg portion, the heel portion, the foot 40 portion and the toe portion of a stocking including a vertically movable thread finger supported on the dial frame and normally disposed in cooperative relation to the needles, a stationary cam ring mounted in the head, a stitch cam 45 on said ring, a sinker cam ring mounted on the cylinder, and a plurality of sinkers, and an auxiliary set of instrumentalities for knitting at least one extra course in the leg and foot portions when the cylinder is being rotated, said auxiliary set 50 functioning subsequent to the main set and including a vertically movable thread finger mounted on the dial frame and normally disposed in cooperative relation to the needles, a horizontally reciprocating stitch cam mounted on 55 the head and normally disposed in cooperative relation to the needles, a horizontally disposed lever fulcrumed on the sinker ring, an auxiliary cam fixed to said lever and normally disposed in cooperative relation to said movable stitch 60 cam, a spring engageable with the lever for normally urging said auxiliary cam upwardly to said inoperative position, springs for respectively maintaining the thread finger and the auxiliary 65 stitch cam in their normal positions, and operating connections between the drum, the thread finger and the movable stitch cam for moving said finger and cam away from their normal positions during the knitting of the heel and toe 70 portions of the stocking, said operating connections including a thrust rod having an extension overlying the cam-carrying lever and normally retaining said lever against upward movement.

2. In a circular knitting machine, the com- 75

- bination with a circular head, of a reciprocatory stitch cam mounted on the head for horizontal radial movements, a vertical lever fulcrumed intermediate its ends to the periphery of said head,
5 a link connecting the upper end of the lever with said cam, a horizontal rock shaft located below said head and journaled thereon, a rock arm fixed to said rock shaft and having pivotal connection with the lower end of said lever, and a pattern
10 drum for actuating the rock shaft.
3. The combination with a circular knitting machine having a needle cylinder and a main knitting station with yarn feeding means and knitting cam mechanisms, of a plurality of auxiliary knitting stations spaced apart and from said
15

main knitting station circumferentially of said cylinder, yarn feeding means at said auxiliary stations respectively, stitch cams at said auxiliary stations respectively, means for simultaneously moving said yarn feeding mechanisms between operative and inoperative positions, means for simultaneously moving said stitch cams between operative and inoperative positions, said auxiliary stations when active being adapted to knit a corresponding number of courses in addition to the course knit at the main station, and a single set of yarn clamping and cutting devices for acting on the yarns fed at all of said auxiliary stations.

ARTHUR A. CAUDLE. 15
